UNITED STATES PATENT OFFICE.

HENRY BUERMANN, OF NEWARK, NEW JERSEY.

DESIGN FOR A CHEEK-PIECE FOR BITS.

45,788.

Specification for Design.

Patented May 19, 1914.

Application filed March 21, 1914. Serial No. 826,439. Term of patent 14 years.

To all whom it may concern:

Be it known that I, HENRY BUERMANN, a citizen of the United States, residing at Newark, county of Essex, and State of New Jersey, have invented a new, original, and ornamental Design for Cheek-Pieces for Bits, of which the following is a specification, reference being had to the accompanying drawing, forming part thereof.

Figure 1 is a side view of my new cheek-

piece for bits, and Fig. 2 is an edge view thereof.

I claim:

The ornamental design for a cheek-piece for bits, as shown.

HENRY BUERMANN.

Witnesses:

W.M. H. CAMFIELD,
GEORGE BUERMANN.
